UNITED STATES PATENT OFFICE.

PETER FORG, OF SOMERVILLE, MASSACHUSETTS.

HINGE.

SPECIFICATION forming part of Letters Patent No. 374,788, dated December 13, 1887.

Application filed January 11, 1887. Serial No. 224,012. (No model.)

To all whom it may concern:

Be it known that I, PETER FORG, of Somerville, county of Middlesex, and State of Massachusetts, have invented an Improvement in 5 Hinges, of which the following description, in connection with the accompanying drawings, is a specification, like letters on the drawings representing like parts.

This invention has for its object to provide 10 a friction-hinge for mirrors and other articles having one part stationary or fixed and another part adapted to be turned to occupy a position at an angle to the fixed part.

Prior to my invention cast-metal hinges, especially those used on mirrors in furniture, have been made with feet having cup-shaped ears, the said ears being concaved or cup-shaped on their inner faces to receive a spiral spring. So, also, hinges have been made with 20 one ear flat and the other cup-shaped on its inner face and receiving a spiral spring within it and having a flat washer on the bolt uniting the ears.

Hinges have heretofore been made of sheet 25 metal struck up at right angles and the halves connected by interposed rubber and metal washers and a transverse bolt provided with a nut and a coiled spring interposed between the nut and one-half of the hinge.

30 My invention consists of a wrought-metal friction-hinge composed of two halves struck up from sheet metal, with feet and ears, the said ears being flat and in contact throughout the area of their adjacent faces, concavo-convex spring washers or disks being arranged on 35 the outer face of each ear and having other than round holes therein to receive a rivet which turns with the washers and ears and unites the halves of the hinge to secure uniform or constant spring action or wear, substantially as hereinafter particularly set forth and claimed.

Figure 1 is a top or plan view of a sheet-metal friction-hinge made in accordance with 45 my invention; Fig. 2, a vertical section of Fig. 1 on line $x x$; Fig. 3, a detail of a washer; and Fig. 4, a view of a sheet-metal strip or blank, showing the shape of the blank for the half of a hinge before it is struck up to form an ear, 50 the part to form the ear being indicated by dotted lines.

The sheet-metal strip A, of Bessemer steel and of the width desired for the hinge, is subjected to the action of a cutting die not herein shown, but of the shape it is required the leaf 55 should have before being struck up and substantially such as shown at a in the full and dotted lines, Fig. 4, the said die at the cutting operation also stamping out the holes a^2 a^3 . The blank so made and marked a is then struck 60 up by a die, in usual manner, into the shape shown in Figs. 1 and 2, to form feet a^x and a flat ear, a^4 , substantially at a right angle to the feet a^x , the said ear being substantially flat or smooth on its inner face. 65

To form my improved friction-hinge two halves such as described are taken and placed with the inner faces of the smooth flat ears a^4 in contact, as shown in Figs. 1 and 2, and a rivet, b , is passed through the holes a^3 in said 70 ears. Upon the rivet b , and bearing against the outer face of each ear a^4 , is a concavo-convex disk or spring-washer, b' , the concaved side of the said disk or washer being next to the said ear, the said disk being convexed at 75 its circumference to form a smooth or rounded contact-surface with the ear, thus preventing a cutting action of the said disk upon the said ear when the latter is turned.

The parts enumerated and comprising the 80 hinge are secured closely together by means of the rivet b , which is headed in usual manner.

In the application of my invention one-half of the hinge will be screwed or otherwise secured to the fixed or stationary part of the article—such, for instance, as the mirror-frame—while the other leaf will be secured to a movable part, as a mirror, there being one at each side of the said mirror. When the mirror is tipped or moved to any desired position, the 85 leaf secured thereto will turn on the rivet b as on a pivot, and it will be maintained in the said position by the friction between the smooth flat inner faces of the ears of the movable and stationary leaf, the said friction being sufficient to so maintain the mirror in its 90 position until the latter is positively moved.

The washers or disks b' , owing to their concaved shape, act as springs to force the ears a^4 together, the said spring-washers or disks 95 compensating for any wear upon or irregularities on the inner face of said ears. The open-

ing in the washer through which the rivet *b* is extended is square or rectangular or other than round shape, to prevent the said washer from rotating or turning on the rivet when the 5 movable leaf of the hinge is turned, the position of the said washer with relation to the ear against which it presses being thus maintained always the same, so that the spring action of the said washer against the ear will be sub-
stantially uniform or constant.

By employing two concavo-convex spring-washers, one for each ear, each washer bearing against the outside of the ear with which it is in contact, and having a square or rectangular or other than round hole, through which the rivet is extended, I am enabled to obtain a much greater friction between the two ears than if a single washer were employed. Furthermore, by making the hole through which the 15 rivet is extended square or other than round the spring-washer is prevented from rotating on the rivet, and a side friction is obtained between the ear and the outer side of the spring-washer, as well as between the two ears.

20 25 I do not herein broadly claim a spring-

washer in combination with a single hinge, as that forms the subject-matter of another application filed concurrently herewith.

I claim—

The wrought-metal friction-hinge consisting of two halves struck up from sheet metal, with feet *a*^x and ears *a*⁴, which latter are flat and in contact throughout the area of their adjacent faces, concavo-convex spring-washers or disks *b*', arranged one on each ear and 30 having other than round holes therein, and a rivet, *b*, secured in said washers and turning with them and with the ears and passed through the ears and uniting the halves of the hinge, whereby the spring action and wear 35 40 are uniform or constant, substantially as shown and described.

In testimony whereof I have signed my name to this specification in the presence of two subscribing witnesses.

PETER FORG.
